UNITED STATES PATENT OFFICE.

JOHN A. ANDERSON, OF BOSTON, MASSACHUSETTS.

TIMER.

1,420,612.

Specification of Letters Patent. Patented June 20, 1922.

Application filed March 13, 1920. Serial No. 365,406.

To all whom it may concern:

Be it known that I, JOHN A. ANDERSON, a citizen of the United States, residing at Boston, in the county of Suffolk and State 5 of Massachusetts, have invented new and useful Improvements in Timers, of which the following is a specification.

This invention relates to improvements in timers, also known as commutators, for use 10 in connection with gasoline engines.

It is the object of the invention to provide a simple, practical device capable of making a perfect electric contact at all speeds, for timing the instant at which the 15 spark plugs of a gasoline engine will fire.

It is also an object of the invention to provide a device which will not require lubrication, thereby eliminating the danger of short circuiting the electric current and 20 also making it easier to start the engine because of the absence of oil upon the contact members.

The invention consists in the combination and arrangement of parts whereby the 25 above objects and certain other objects hereinafter appearing, may be accomplished as set forth in the following specification and particularly pointed out in the claims thereof.

30 Referring to the drawings:

Figure 1 represents a cross sectional view of a casing with a timer mechanism embodying my invention, mounted therein.

Fig. 2 is a vertical section taken on the 35 line 2—2 of Figure 1.

Fig. 3 is a detail horizontal section taken on the line 3—3 of Fig. 1.

Fig. 4 is a detail horizontal section taken on the line 4—4 of Fig. 1.

40 Like numerals refer to like parts throughout the several views of the drawings.

In the drawings, 5 represents a casing upon which are mounted a plurality of stationary contact members 6. There may be any number of the stationary contact members 6 according to the number of cylinders comprising the engine; in this instance, however, there are 4 in number, being evenly spaced around the circumference of the casing 5 and insulated therefrom by members 7 and 8. The insulating member 7 is located upon the inner side of the casing 5 and extends therethrough being surrounded upon the exterior of the casing by 55 the member 8. The stationary contact members 6 are each provided with extensions 9

which extend through the insulating members 7 and 8 respectively, a nut 10 simultaneously clamping said insulated members to the casing 5 and securing said stationary contact members within the insulating members. 60 Thumb-nuts 11 have screw threaded engagement with the outer end of the extensions 9 and serve to connect electric wires 12 thereto.

Each stationary contact member 6 is provided upon its inner end with a transversely extending slot 13 through which a contact member 14 is adapted to rotate and contact with the sides thereof. The opposite ends of the slots 13 are flared at 15 to facilitate the 70 passage of the rotary contact member 14 therethrough. The rotary contact member 14 is fastened to a sleeve 16 which, in turn, is fastened to a shaft 17 by a pin 18 and is therefore rotatable therewith. The sleeve 75 16 and shaft 17 together constitute a rotary driving member. A grounded wire from a magneto or some other source of electric supply, allows an electric current to flow through the various metal parts of the engine and 80 thereby into the shaft 17. The rotary contact member 14 consists of a pair of parallel contact plates 21 and 22 which are pivoted upon studs 23, the said studs being secured by pins 24 to projections 25 formed 85 integral with the sleeve 16 and which project laterally from opposite sides thereof. The contact plates 21 and 22 are each provided with ears 26 and 27 respectively which are bent at right angles thereto, the studs 23 90 passing through each of said ears and forming pivots upon opposite sides of the sleeve 16 which are common to each contact plate.

The contact plates are each provided with a foot 28 the tip ends of which are bent toward each other at 29. A spring 30 is located between the contact plates 21 and 22 being supported upon pins 31, and tends to force the foot 28 of each contact plate away from the other and force a projection 32 formed integral with the contact plate 21 against the contact plate 22 when the feet 28 are not passing through the slots 13 of the contact members 6. A spring 33 is mounted upon the upper side of the sleeve 16, opposite extremities of said spring terminating adjacent to the inner surface of the contact plates 21 and 22, thereby positioning the rotary contact member upon the sleeve 16 in order that the feet 28 thereof 110 will properly align with the slots 13 of the stationary contact members and allow said

rotary contact member 14 to rock slightly as a unit upon the studs 23 if for any reason the shaft 17 should be slightly out of alignment and thereby not rotate perfectly true.

- 5 The general operation of my improved timer is as follows: As the shaft 17 is rotated by suitable mechanism not shown in the drawings, but well known to those skilled in the art, the rotary contact member 14 will 10 rotate therewith, the foot 28 of each contact plate passing through the slot 13 of each stationary contact member 6. The feet 28 will contact with the walls at each side of the slot 13 and thereby complete an electric circuit successively through each stationary contact member 6. The tips of each foot are bent inwardly and the ends of each slot are flared outwardly thereby facilitating the passage of said feet through said slots. As 15 the feet pass through the slots 13 they will yield inwardly slightly against the pressure of the spring 30 which always tends to force them away from each other, the stop 32 limiting said movement.
- 20 25 If the sides of the feet wear from contact with the walls of the slots 13, the tip end of the stop 32 may be filed away slightly to compensate for the wear upon the sides of the feet. The contact plates 21 and 22 are 30 so mounted relatively to the other that they may rock independently or in unison upon the studs 23. The stationary contact members 6 will always wear smooth and even, thereby allowing a perfect electric contact 35 to be made at any speed at which the rotary contact member 14 may be driven.

Having thus described my invention, what I claim and desire by Letters Patent to secure is:

- 40 1. A device of the character described having, in combination, a casing, a plurality of stationary contact members attached to said casing and insulated therefrom, a rotatable driving member, and a rotatable contact member pivotally attached to said rotatable driving member upon opposite sides of the axis thereof and adapted to successively engage said stationary contact members and complete an electric circuit therethrough.
- 45 2. A device of the character described having, in combination, a casing, a plurality of stationary contact members attached to said casing and insulated therefrom, a rotatable driving member, and a rotatable contact member surrounding said rotatable driving member, and pivotally attached thereto upon opposite sides of the axis thereof and adapted to successively engage said stationary contact members and complete an electric circuit therethrough.
- 50 3. A device of the character described having, in combination, a casing, a plurality of stationary contact members attached to said casing and insulated therefrom, a rotatable driving member, a rotatable contact member pivotally attached thereto upon opposite sides of the axis thereof and adapted to engage said stationary contact members and complete an electric circuit therethrough.
- 55 65

pivotally attached to said rotatable driving member upon opposite sides of the axis thereof and adapted to successively engage said stationary contact members and complete an electric circuit therethrough, and resilient means adapted to position said rotatable contact member relatively to said rotatable driving member.

4. A device of the character described having, in combination, a casing, a plurality of 70 stationary contact members attached to said casing and insulated therefrom, each of said stationary contact members being provided with a transversely extending slot, a rotatable driving member, a rotatable contact member pivotally attached to said rotatable driving member upon opposite sides of the axis thereof and adapted to successively engage said stationary contact members and complete an electric circuit therethrough, 75 said rotatable contact member being arranged to pass through the transverse slots of said stationary contact members during its rotation.

5. A device of the character described having, in combination, a casing, a plurality of 80 stationary contact members attached to said casing and insulated therefrom, a rotatable driving member, and a rotatable contact member embodying therein a plurality of contact plates pivotally mounted upon said rotatable driving member upon opposite sides of the axis thereof, each having a foot formed integral therewith adapted to engage said stationary contact members 85 and complete an electric circuit there-through.

6. A device of the character described having, in combination, a casing, a plurality of 90 stationary contact members attached to said casing and insulated therefrom, a rotatable driving member, a rotatable contact member embodying therein a 95 plurality of contact plates pivotally mounted upon said rotatable driving member upon opposite sides of the axis thereof, each having a foot formed integral therewith adapted to engage said stationary contact members and complete an electric circuit there-through.

7. A device of the character described having, in combination, a casing, a plurality of 100 stationary contact members attached to said casing and insulated therefrom, a rotatable driving member, a plurality of contact plates surrounding said rotatable driving member and pivotally attached thereto upon opposite sides of the 105 axis thereof, each of said contact plates being provided with a foot formed integral therewith adapted to engage said stationary contact members and complete an electric circuit there-through, and means inserted between said 110 contact plates adapted to force said feet of the members away from each other.

115 8. A device of the character described having, in combination, a casing, a plurality of 120 stationary contact members attached to said casing and insulated therefrom, a rotatable driving member, a plurality of contact plates surrounding said rotatable driving member and pivotally attached thereto upon opposite sides of the 125 axis thereof, each of said contact plates being provided with a foot formed integral therewith adapted to engage said stationary contact members and complete an electric circuit there-through.

8. A device of the character described having, in combination, a casing, a plurality of stationary contact members attached to said casing and insulated therefrom, a shaft, a sleeve rotatable with said shaft, a plurality of contact plates surrounding said sleeve and pivotally attached thereto upon opposite sides of the axis thereof, each of said contact plates being provided with a foot formed integral therewith adapted to engage said stationary contact members and complete an electric circuit therethrough, and a spring located between said contact plates and adapted to force said feet of the members apart.

9. A device of the character described having, in combination, a casing, a plurality of stationary contact members attached to said casing and insulated therefrom, a shaft, a sleeve rotatable with said shaft, a plurality of contact plates surrounding said sleeve and pivotally attached thereto upon opposite sides thereof, each of said contact plates being provided with a foot formed integral therewith adapted to engage said stationary contact members and complete an electric circuit therethrough, a spring located between said contact plates and adapted to force said feet of the members apart, and a stop formed integral with one of said contact plates adapted to limit the movement of said feet apart.

10. A device of the character described having, in combination, a casing, a plurality of stationary contact members attached to said casing and insulated therefrom, a shaft, a sleeve rotatable with said shaft, and a ro-

tatable contact member pivotally attached to said sleeve upon opposite sides of the axis thereof, said rotatable contact member embodying therein a plurality of contact plates, each having a foot formed integral therewith adapted to engage said stationary contact members and complete an electric circuit therethrough, said contact plates being adapted to rock independently or in unison upon pivots common to each.

11. A device of the character described having, in combination, a casing, a plurality of stationary contact members attached to said casing and insulated therefrom, a shaft, a sleeve rotatable with said shaft, and a rotatable contact member pivotally attached to said sleeve upon opposite sides thereof, said rotatable contact member embodying therein a plurality of contact plates, each having a foot formed integral therewith adapted to engage said stationary contact members and complete an electric circuit therethrough, said contact plates being adapted to rock independently or in unison upon pivots common to each, and a spring attached to said sleeve and located between said contact plates and adapted to position said rotatable contact member upon said sleeve to engage said stationary contact members.

In testimony whereof I have hereunto set my hand in presence of two subscribing witnesses.

JOHN A. ANDERSON.
